UNITED STATES PATENT OFFICE.

OTTO HERMANN HARTMANN, OF CASSEL-WILHELMSHOHE, GERMANY, ASSIGNOR TO
SCHMIDT'SCHE HEISSDAMPF GESELLSCHAFT, OF CASSEL-WILHELMSHOHE, GERMANY, A CORPORATION OF GERMANY.

STEAM AND WATER COLLECTOR FOR HIGH-PRESSURE BOILERS.

Application filed December 5, 1922, Serial No. 605,004, and in Germany December 27, 1921.

There are considerable difficulties in the manufacture of riveted reservoirs for boilers for high working pressures particularly of 30 atm. and more, for the reservoirs for the steam- and water-collectors used which have comparatively small diameters of about 1000 to 1200 m/m. require such a thickness of the rivets that is impossible to 5 clench the latter by hand. Machine-riveting can be carried out satisfactorily only if the flanged edges of both bottoms are directed outwards. According to the prevailing practice the bottoms of the steam- and water-collectors are manufactured of boiler 10 plate, the edge being flanged. This can only be done if the bottom plate proper is connected with the edge by a curved portion. Therefore it is impossible to form an 15 inner caulking edge for tightening purposes on the bottoms used so far. If a caulking edge on such bottoms is intended to be produced this would only be possible at the outer edge (looking lengthwise of the boiler or reservoir). With high pressures, particularly 20 those of the order mentioned above, the production of a safe tight joint seems to be impossible in this way. Therefore the manufacture of riveted steam- and water-collectors has been considered out of the 25 question hitherto.

Now, according to the invention this problem is solved in a simple and reliable way by inserting the bottoms of the boiler which are provided with an outwardly extending flange in such a manner into the shell of the boiler that the riveting of the joint may be effected from the outside, whereas the tightening of the joint is effected from the interior of the boiler by 30 caulking that portion of the bottom which is adjacent to the inner surface of the boiler. In order to enable the formation of a caulking edge, the bottom of the boiler is to be manufactured as a forged piece or 35 casting, having a suitable shape of the edge. With this invention it is now possible to have the bottoms of the boiler jointed with the shell by riveting; even for very high working pressures.

50 An example of the invention is illustrated by the accompanying drawings, in which Fig. 1 is a longitudinal section of a boiler, drum, or reservoir, with parts broken away; Fig. 2 is an end view looking from the right

of Fig. 1; Fig. 3 is a longitudinal section showing part of the right hand portion of Fig. 1 upon an enlarged scale; and Fig. 4 is an enlarged longitudinal section of a slightly different construction. The reservoir consists of the shell A and the bottoms 55 or heads B. Each of the latter is provided with a flange c which bears against the relatively thin part d of the shell A. This portion of reduced thickness is formed by machining (turning off, etc.). Rivets connect the bottom with the shell. At e (Fig. 3) a caulking edge is produced. Instead of the caulking edge a caulking ring f may be used with the same effect (see Fig. 4). The purpose of reducing the thickness of the 60 shell A at d is to facilitate the riveting operation, since it enables smaller rivets to be used. It will be noted that the head B has an annular surface perpendicular to the inner surface of the shell A, so that the 65 pressure exerted during caulking will properly close the joint instead of tending to open it. Such inner surface of the shell A is smooth, or at least of uniform diameter, at the portion in contact with the head or 70 bottom B and immediately adjacent to said contact portion.

I claim:—

1. A structure of the character described, comprising a tubular shell and a bottom 75 fitted into the end portion of such shell, said bottom comprising a body portion extending transversely of the axis of the shell and an outwardly directed flange extending 80 lengthwise of the shell and riveted to the inner surface of that portion of the shell which projects beyond said body portion of the bottom, said body portion extending close to the inner surface of the shell and having an annular sharp edge in contact 85 with said inner surface to form an annular caulking surface to obtain a tight interior joint between the shell and the bottom.

2. A structure of the character described, comprising a tubular shell and a bottom 90 fitted into the end portion of such shell, said bottom comprising a body portion extending transversely of the axis of the shell and an outwardly directed flange extending 95 lengthwise of the shell and riveted to the inner surface of that portion of the shell which projects beyond said body portion of the bottom, said body portion extending 100

close to the inner surface of the shell and having an annular surface perpendicular to said surface and adjacent thereto to facilitate the formation of a caulked interior joint between the shell and the bottom.

3. A structure of the character described, comprising a tubular shell and a bottom fitted into the end portion of such shell, said bottom comprising a body portion extending transversely of the axis of the shell and an outwardly directed flange extending lengthwise of the shell and riveted to the inner surface of that portion of the shell

which projects beyond said body portion of the bottom, the inner surface of the shell being of uniform diameter at the portion in contact with such bottom and immediately adjacent to said contact portion, and said body portion extending close to such inner surface of the shell and having an annular surface substantially perpendicular to said inner surface of the shell and immediately adjacent thereto to facilitate the formation of a caulked interior joint between the shell and the bottom.

OTTO HERMANN HARTMANN.
